UNITED STATES PATENT OFFICE.

WILLIAM E. FICKLEN, OF NEW YORK, N. Y.

STREET-PAVEMENT.

1,098,792.

Specification of Letters Patent.

Patented June 2, 1914.

Application filed August 21, 1909. Serial No. 513,920.

To all whom it may concern:

Be it known that I, WILLIAM E. FICKLEN, a citizen of the United States, and a resident of the city of New York, county of New York, and State of New York, have invented certain new and useful Improvements in Street-Pavements, of which the following is a specification.

This invention relates to street pavements and the like.

The objects of the invention are to improve and simplify the construction of street pavements, as well as to decrease the expense attending their construction and maintenance, and to increase their durability.

With the foregoing and other objects in view, which will appear as the description proceeds, the invention resides in the combination and arrangement of parts, forming a street pavement, and in the details of construction hereinafter described and claimed, it being understood that changes in the particular embodiment of invention herein disclosed may be made within the scope of the claims, and as indicated by the differences in the claims, without departing from the spirit of the invention.

The combination and arrangement of parts which I have discovered to be effective in producing a strong, simple, durable and relatively inexpensive pavement, includes, first, an earth roadbed, by which I mean either the natural earth as graded and prepared for the reception of paving materials or a foundation prepared by the use of sand, gravel, ashes, cinders, loose crushed stone, or the like, which roadbed is characterized by the fact that it is relatively inert and nonbuckling under various weather conditions; second, a crust laid directly on the earth roadbed and comprising a plurality of concrete sections of relatively large area, capable of "creeping" on the earth foundation, or otherwise responding to sun-power, weather and traffic conditions; third, expansion joints separating the concrete sections and extending from the top of the pavement to the roadbed, so as completely to divide the sections into separate monoliths; and fourth, reinforcing means embedded in and carried by the concrete sections at the upper portions of those expansion joints which require reinforcement, said reinforcing means being of any suitable construction and forming, in effect, a component part of the concrete sections interwoven and mov-

ing therewith and conforming thereto during the setting of the concrete and during the creeping of the sections, and receiving traffic shocks concurrently with the concrete, thereby having little or no tendency to work loose from the concrete, and being supported by the concrete out of engagement with the earth roadbed.

In the accompanying drawings forming part of this specification,—Figure 1 is a cross section showing a suitable earth roadbed, with the creeping monolithic sections disposed thereon and completely separated by the expansion joints, said sections having component reinforcing means applied and carried by such edges as require reinforcement, out of contact with the roadbed. Fig. 2 is a plan view of the construction shown in Fig. 1. Fig. 3 is a side elevation of one form of reinforcing means; Fig. 4 is an end view of the reinforcing member shown in Fig. 3. Figs. 5 and 6 are cross sectional views showing modified means for reinforcing the expansion joints. Fig. 7 is a detail view of the reinforcing means shown in Fig. 6. Fig. 8 is a cross sectional view showing another reinforcing means in a joint located near a curb. Figs. 9 and 10 are respectively a plan and a side elevation of the reinforcing member shown in Fig. 8.

Like reference numerals indicate corresponding parts in the different figures of the drawings.

In constructing a pavement according to my invention, I preferably prepare an earth roadbed, as shown in Fig. 1. This roadbed may consist of either the natural earth graded and prepared for the reception of paving materials, or any suitable foundation prepared by the use of sand, gravel, ashes, cinders, loose crushed stone or other suitable material, which roadbed preferably is characterized by the fact that it is relatively inert under various weather conditions.

Superposed directly upon the roadbed is a crust comprising a plurality of substantially rectangular unit concrete sections 1 of relatively large area. These sections 1 may be of any desired shape.

The large concrete sections 1 are separated from each other by expansion joints 2 which extend from the surface of the pavement to the inert roadbed and serve completely to divide the crust into separate monoliths or sections.

The problem of protecting the edges of

the separate sections or monoliths 1 is attended with difficulties, owing to the considerations: (1) that the reinforcement must be such as to follow the concrete as it sets and to move with the section during its various adjustments or so-called creeping or crawling movements under varying sun-power, weather and traffic conditions; (2) that it must remain permanently in combination with the unit concrete sections and not be loosened or separated therefrom under the various conditions to which it is subjected; (3) that it must be relatively inexpensive; and (4) that it must not only protect the edges of the expansion joint, but so far as necessary, reinforce and strengthen the unit concrete sections. I meet these and other inherent conditions by employing any suitable form of reinforcement, which is embedded in and carried by and on those upper portions of the edges of the concrete sections which require strengthening, the reinforcement forming, in effect, a component part of the concrete section.

One example of reinforcement 3 is illustrated in Figs. 3 and 4. This reinforcement 3 includes an upper bar 5 which is designed to set into the surface of the section or monolith 1 and to be held in position thereon preferably by means of interweaving members 11 and 12, which are formed by suitably shearing or cutting the bar 1 and bending down the interweaving members 11 and 12 at the point marked 9, thus producing the openings 7 in the bar 5. In the construction of the pavement, the openings 7 are filled with concrete which is thus exposed on the surface of the pavement and serves the purposes,—(1) of providing anti-slipping surfaces, and (2) of so interlocking or interweaving the bar 5 with the concrete that it not only sets therewith, but forms a component part thereof throughout the life of the pavement. The reinforcement 3 is also provided with the bar or wing 6 which is disposed at a right angle to the bar 5, and is interwoven with the face of the concrete section within the expansion joint. The bar 6 is formed with the interweaving or anchoring members 13 and 14 which preferably are formed by suitably shearing the bar 6 and bending said members inward, as indicated at 9, thereby producing the openings 8, which are filled with concrete and serve to rivet or interweave the bar 6 with the concrete, thus causing the bar to become, in effect, a component part of the section during the setting operation and subsequently.

The wings 5 and 6 of the reinforcement 3 are preferably formed integral with each other, as indicated at 4.

Another example of reinforcement is indicated in Fig. 5, wherein the two wings or bars 17 and 18 are formed integral with

each other, as indicated at 16 and are provided with interweaving or anchoring members 19 in the form of bolts which are embedded in the concrete.

Another example of reinforcement is indicated in Figs. 6 and 7, wherein the horizontal bars 20 are formed at the inner edges thereof with interweaving members or flanges 21 which are inclined and formed with teeth or serrations 23. The vertical wings 22 are provided with inclined serrations 24 which form interweaving members.

Another example of reinforcement 30 is disclosed in Figs. 8, 9 and 10. The reinforcement 30 comprises a vertical bar 31 which is set into and supported by the concrete section 1, at the expansion joint and is formed with a plurality of inwardly extending wings or interweaving members 32, each having at the inner end thereof a downwardly projecting tooth 33. Each of the wings 32 is formed with an opening 35, through which the concrete sets.

As indicated in Fig. 2, the reinforcements are set along the upper portions of those expansion joints which require reinforcement. For instance, the edges of the outer monoliths below the curb reinforcements 15 usually do not require to be reinforced. The reinforcements on the remaining sections 95 usually continue along all the edges of the section, but in some cases the reinforcements may be omitted, or, as indicated in Fig. 8, the reinforcement 31 may be applied to one section 1 and the adjoining section 1 may be 100 constructed without a reinforcement.

In fitting the longitudinal and transverse reinforcements to a monolith or section 1, the ends of said reinforcements are preferably cut on diagonal lines, and these diagonal edges are set a slight distance away from each other, so as to permit the reinforcements to move with the concrete during the slight shrinking thereof at the time it sets.

As shown in Figs. 1, 5, 6 and 8, the reinforcements are embedded in and supported by the concrete section above and out of contact with the earth roadbed, thus causing the reinforcement to form, in effect, a component part of the section, the face of the reinforcement within the expansion joint being flush with the face of the concrete section below the reinforcement. The advantages of this arrangement of the reinforcements are: (1) the reinforcements strengthen and bind each unit section and thus prevent it from splitting or cracking from its own weight or from other causes during the powerful reactions to which the sections are subjected from heat, weather and traffic conditions; (2) the reinforcements are so interwoven with the concrete and are so supported thereby that they move therewith during the setting operation, and thus have no tendency to be loosened by the concrete 130

shrinking away therefrom; (3) the reinforcement forms such a component part of the unit concrete sections that the shocks received by the concrete and reinforcements are practically concurrent or identical, so that there is no tendency to loosen or separate the concrete and its reinforcement.

The pavement of the present invention is strong, simple, durable and inexpensive in construction, as well as thoroughly practical and efficient in use.

I claim—

1. A pavement comprising an earth roadbed, a crust supported directly on said roadbed and comprising a plurality of concrete sections of relatively large area separated from each other by expansion joints extending from the top of the pavement to the roadbed, and reinforcing means embedded in and carried by and continuing along the upper portions of the edges of the concrete sections at the joints which require reinforcement.

2. A pavement comprising an earth roadbed, a crust supported directly on said roadbed and comprising a plurality of concrete sections of relatively large area separated from each other by expansion joints extending from the top of the pavement to the roadbed, said sections being formed with shoulders within the expansion joints, and reinforcing means embedded in and carried by and continuing along the upper portions of the edges of the concrete sections at the joints which require reinforcement, said reinforcing means consisting of metal strips located on edge within the expansion joints and resting upon said shoulders formed in the concrete.

3. A pavement comprising an earth roadbed, a crust supported directly on said roadbed and comprising a plurality of concrete sections of relatively large area separated from each other by expansion joints extending from the top of the pavement to the roadbed, and reinforcing means embedded in and carried by and continuing along the concrete sections at the joints which require reinforcement, said reinforcing means consisting of metal strips set into the upper surfaces of the concrete sections along the expansion joints.

4. A road pavement comprising an earth roadbed and rectangular unit concrete sections supported directly on said roadbed and constituting a checkerboard arrangement, said sections being separated from each other wherever opposed by another section by expansion joints extending from the surface of the pavement to the roadbed, each section being armored along the upper edges of each expansion joint.

5. A sheet pavement of concrete consisting of relatively large unit areas or sections completely separate from but contiguous to

each other, said areas or sections having expansion joints between them extending from the surface thereof to the earth or sub-base of ashes, gravel or the like constituting the roadbed, each of said unit sections being bound by a continuing band of metal set into the concrete upon the surface thereof at the upper edges of the expansion joints, said metal band extending entirely around each unit section or area of concrete at the expansion joints and serving to bind the same.

6. A sheet pavement of concrete consisting of relatively large unit areas or sections completely separate from but contiguous to each other, the said unit areas or sections having expansion joints between them extending from the surface thereof to the earth or sub-base of ashes, gravel or the like constituting the roadbed, the upper edges of each unit section at the expansion joints being embraced by a continuing metallic band set into and overlying the exposed upper edges of the sectional unit of concrete and which band is supported thereby and extends entirely around the same at the expansion joints to protect the edges thereof and to bind and hold and keep intact each unit area or section to which the metallic band is applied.

7. A sheet pavement of concrete consisting of large unit areas or sections completely separate from but contiguous to each other, the said unit areas or sections having expansion joints between them extending from the surface thereof to the earth or sub-base of ashes, gravel or the like constituting the road-bed, each unit section being bound at the upper exposed edges of the expansion joints by a continuing metallic band set into the said unit areas or sections to protect the edges thereof at the expansion joints and to bind and keep intact each unit area or section.

8. A roadway comprising a series of relatively large sections formed of concrete the said sections having their confronting edges spaced apart to provide expansion joints between them, also having their upper edges provided with corner protectors, the material of the corner protectors being removed or broken away at intervals to form anti-slipping surfaces next to the outer edges of the corner protectors.

9. A pavement for roadways, comprising a series of relatively large sections formed of concrete, said sections having their confronting edges spaced apart to provide expansion joints between them and also having their upper surfaces adjacent to their said edges provided with metal corner protectors having spaced openings therein adjacent to the outer edges thereof, the said openings being arranged to receive the concrete and to expose the upper surface thereof whereby the upper surfaces of the sec-

tions adjacent to the edges of the latter are formed of metal and concrete arranged alternately to form an anti-slipping surface.

10. A pavement for roadways, comprising a series of relatively large sections formed of concrete, the said sections having their confronting edges spaced apart to provide expansion joints between them, metallic protectors for said edges, said protectors 10 being of angle construction and having members which cover the edges of the sections and other members which lie upon the upper surfaces of the section adjacent to said edges, the latter members having openings which are spaced apart and are arranged to receive the concrete of the sections and to expose the upper surface of the latter to form an anti-slipping surface.

11. A pavement for roadways, comprising a series of relatively large sections formed of concrete, the said sections having their confronting edges spaced apart to provide expansion joints between them, metallic protectors for said edges, said protectors 25 being of angle construction and having members which cover the edges of the sections and other members which lie upon the upper surface of the section adjacent to said edges, the latter members having openings 30 which are spaced apart and are arranged to receive the concrete of the sections and to expose the upper surface of the latter, said

members also having anchoring projections embedded in the concrete to form an anti-slipping surface.

12. A pavement for roadways, consisting of a sheet of hydraulic cement laid directly on the earth, constituting the bed of the roadway, said sheet formed with one or more longitudinal lines of division and 40 with a series of transverse lines of division, all of the said lines of division extending entirely through the sheet to the bed of the roadway and the transverse lines intersecting the longitudinal lines, said lines being 45 relatively so arranged that the sections bounded thereby will each be of large area whereby each section is movable and expandable as a unit independently of every other, strips of metal set into and protecting the 50 edges of each section, said strips of metal having upper portions which lie upon the surfaces of the sections adjacent the edges and are formed with openings which are spaced apart and are arranged to receive the 55 hydraulic cement and to expose the upper surface of the latter.

In testimony whereof, I have signed my name to this specification, in the presence of two subscribing witnesses.

WILLIAM E. FICKLEN.
